METHOD AND APPARATUS FOR REMOVAL
OF AMMONIA IN BOILER FEEDWATER
SYSTEMSJoseph F. Sebald, Bloomfield, N. J., assignor to
Worthington Corporation, Harrison, N. J., a
corporation of Delaware

Application January 8, 1949, Serial No. 69,926

17 Claims. (Cl. 183—2.5)

1

This invention relates to boiler feedwater systems of power plants and the primary object of the invention is to provide a method and apparatus for removing ammonia from boiler feedwater.

Ammonia which is present in some degree in the water utilized in boiler systems is detrimental and causes corrosion of copper base alloy metals much of which is used in the apparatus of a boiler feedwater system of a power plant, and the present invention provides means for removal of substantially all of the ammonia from such water by degasification and scrubbing of the water, particularly the water from the evaporator make-up and the condensate from the ejectors employed for withdrawing the non-condensable gases from the system.

With these and other objects in view, as may appear from the accompanying specification, the invention consists of various features of construction and combination of parts, which will be first described in connection with the accompanying drawings, showing a method and apparatus for removal of ammonia and other gases in boiler feedwater systems of a preferred form embodying the invention, and the features forming the invention will be specifically pointed out in the claims.

In the drawings:

Figure 1 of the drawings shows a diagrammatic view of one form of the ammonia and other gases removing method and apparatus.

Figure 2 is a diagrammatic view of another form of the apparatus and method of removing ammonia and other gases from boiler feedwater differing slightly from the system illustrated in Figure 1.

Figure 3 is a diagrammatic view of still another form of the ammonia and other gases removing system wherein an independent condenser is employed for condensing the vapor from the make-up water evaporator instead of utilizing either the inter or after condenser of the ejector for such wear.

Referring more particularly to the system shown in Figure 1 of the drawings, 1 indicates the surface condenser of a boiler feed system which may be of any approved type of surface condenser employed for condensing the exhaust steam from the prime mover such as a turbine or other engine (not shown). As is well known in boiler feed systems, the condensate from the condenser 1 is returned to the boiler for conversion into steam or vapor for reuse. However, non-condensable gases such as oxygen or air leak into

2

the system and to prevent the corrosion and erosion of the various pieces of apparatus in a boiler feed system such non-condensables are removed and in the diagram shown in Figure 1 of the drawings the non-condensables are withdrawn from the condenser 1 by a combination multi-jet ejector and condenser structure 2 of any approved construction. The ejector 2 operates in the usual manner of ejector, withdrawing the non-condensable gases from the condenser 1 with steam as a motive power. The steam utilized in the ejectors is condensed in an inter-condenser 3 for the first stage of the ejector and an after condenser 4 for the last or final stage. Any non-condensables released in the inter and after condensers 3 and 4 by the condensation of the steam or condensable vapors is vented through a suitable vent 5. In the system shown in Figure 1 of the drawings the condensate from the condenser is pumped by a condensate pump 6 through the coils or tubes 7 of the inter and after condensers 3 and 4 and from thence to the boilers through a suitable line 8. All of the above is standard construction and arrangement of apparatus in boiler feed systems. In the present invention the condensate from the inter and after condensers 3 and 4 pass into a suitable condensate or hot well 9 from which it is picked up by a transfer pump 10 and delivered to a degasifier 11.

The degasifier 11 may be of any approved type preferably a direct contact degasifier or feedwater heater such as those disclosed in Patents 2,308,719 or 2,308,721, although any approved type of direct contact degasifier may be employed which will provide substantially complete degasification of the condensate delivered thereto by the pump 10 and at the same time provide a scrubbing action of the condensate by steam. Steam is delivered to the degasifier 11 from any suitable source of steam supply as indicated at 12 and the degasified liquid condensate passes from the storage space at the bottom of the degasifier 11 through a suitable trap 13 back into the condenser 1 through a suitable pipe or conduit 14. The feedwater or condensate from the degasifier 11 while being shown returned to the system through the condenser 1 may be returned into the system at any suitable point without departing from the spirit of the invention.

It is necessary to supply make-up water to the system to compensate for water lost during circulation through the system and such make-up water is delivered from any suitable source of supply (not shown) through suitable conduit 50 means 15 to an evaporator 16 in which the make-

up water is evaporated by steam from any suitable source (not shown) which is delivered to a suitable steam coil 17 within the evaporator and passes from the coil 17 through a suitable conduit 18 into the condenser 1 where it is condensed with the exhaust steam of the system. The vapor from the evaporator 16, that is, the evaporated make-up water delivered thereto is so passed through a suitable conduit 19 into the inter condenser 3 of the evaporator structure 2 where it is condensed and passes with the ejector condensate into the condensate or hot well 9 from which it together with the evaporator condensate is delivered by the transfer pump 10 to the degasifier 11 and it is consequently returned into the system from the degasifier 11 with the degasified ejector condensate.

The ammonia and any other vapors released in the degasifier 11 are vented therefrom to waste or to atmosphere through a suitable vent 20 so that the degasified make-up water and ejector condensate are returned to the boiler feed system practically free of ammonia.

In the modified system shown in Figure 2 of the drawings, the same apparatus as shown in Figure 1 is employed such as, the condenser 1', condensate pump 6', ejector structure 2', inter condenser 3', after condenser 4', hot well 9', transfer pump 10', degasifier 11', and evaporator 16'.

The system shown in Figure 2 differs from the system shown in Figure 1 of the drawings in that the evaporated make-up water is delivered from the evaporator 16' to the after condenser 4', instead of to the inter condenser 3' of the ejector structure. The point to which the vaporized make-up water is delivered, that is whether it is delivered to the inter condenser or the after condenser of the ejector structure depends upon the pressures in the system, some systems making it practical to deliver the evaporated make-up water to the inter condenser while the pressures in other systems will make it practical to deliver the evaporated make-up water to the after condenser of the ejector.

The system shown in Figure 3 of the drawings includes the condenser 1a, condensate pump 6a which delivers the condensate from the condenser through the tubes or coils 7a of the ejector structure 2a for condensing the steam utilized by the ejector structure 2a for withdrawing the non-condensable gases and non-condensed vapor from the condenser 1a. In the structure shown in Figure 3 the condensate from the condenser 1a, after passing through the tubes or coils 7a of the inter condenser 3a and after condenser 4a of the ejector structure 2a is passed through the tubes of a secondary surface type condenser 30 and from thence to the boilers through the conduit 8a. In the system shown in Figure 3 the evaporated make-up water passes from the evaporator 16a through a suitable conduit 31 into the secondary condenser 30 where it is condensed. The condensate from the secondary condenser 30 passes through a suitable conduit 32 into the hot well 9a where it mixes with the condensate from the inner condenser 3a and the after condenser 4a. The mixed condensate is taken from the hot well 9a by the transfer pump 10a and delivered to the degasifier 11a which may be the same construction as the degasifiers 11 and 11' where the condensate is degasified and thoroughly scrubbed by hot steam and the ammonia vapor and any non-condensable vapors released in the degasifier 11a are vented to waste through the vent 20a. The

degasified and scrubbed ejector condensate and condensed make-up water are delivered back into the boiler feed system through the conduit 14a either into the condenser 1a or any other suitable point in the system. The steam utilized in the coil 17a of the evaporator 16a is shown as delivered to the condenser 1a but in practice, this steam may be delivered to the condenser 1a as shown to the secondary condenser 30 or to the degasifier 11a if it is so desired without departing from the spirit of the present invention.

In all three forms of the systems shown, a vent condenser 33 is indicated in the degasifiers and the tubes of such vent condenser are connected to the conduit which delivers the condensate from the condensate pump of the main condenser to the boilers so that a part of the condensate will flow through the vent condensers 33 for condensing any condensable vapor which passes thereto from the degasifier. The use and the construction of such vent condensers with degasifiers or deaerators is well known in the art and such vent condensers are shown in the two abovementioned patents disclosing suitable degasifiers for use in the systems just disclosed. Various traps are installed in the systems, as shown in the drawings for the usual purpose of such traps, that is, to prevent the back flow of the various vapors and condensates flowing through the system.

The term "non-condensable" is employed in the claims to designate all gases, such as carbon dioxide, sulphur dioxide, oxygen, nitrogen, and any of the many other gases which may be present, and which under the temperature and pressure conditions that are found in power plant operation, will not condense.

It will be understood that the invention is not to be limited to the specific construction or arrangement of parts shown, but that they may be widely modified within the invention defined by the claims.

What is claimed is:

1. The method of removal of ammonia from a boiler feed system of a power plant wherein condensate is delivered from a main condenser to a boiler which comprises withdrawing a mixture of non-condensed vapor and non-condensable gas from the main condenser of a boiler feed system, condensing the vapor and thereby releasing the non-condensable gas of the mixture to waste, supplying evaporated make-up water to the boiler feed system at a point in advance of delivery of the condensate to the boiler, mixing the vapor of the evaporated make-up water with the non-condensed vapor and non-condensable mixture withdrawn from the main condenser of the system, condensing the non-condensed vapors of the mixture and make-up water, releasing the non-condensables to waste, heating and scrubbing the condensed vapor with steam and flashing and condensing the heated scrubbed vapor to release the ammonia content of the vapor, venting the released ammonia to waste and delivering the relatively ammonia-free condensate to the boiler feed system at a point in the system in advance of delivery of condensate to the boiler.

2. The method of removal of ammonia from boiler feed systems of power plants as claimed in claim 1 wherein condensate from the main condenser of the boiler feed system is employed as a cooling medium to effect condensation of the vapor of the withdrawn mixture and the vaporized make-up water.

3. The method of removal of ammonia from boiler feed systems of power plants as claimed in claim 1 wherein the condensate is passed from the flashing and condensing operation to the main condenser of the boiler feed system.

4. The method of removal of ammonia from a boiler feed system of a power plant wherein condensate is delivered from a main condenser to a boiler which comprises withdrawing a mixture of non-condensed vapor and non-condensable gas from a main condenser of a boiler feed system, condensing the vapor and thereby releasing the non-condensable gas of the mixture to waste, supplying evaporated makeup water to the boiler feed system at a point in advance of delivery of condensate to the boiler, condensing the non-condensed vapors of the evaporated make-up water, mixing the condensed make-up water with the condensed vapor of the mixture withdrawn from the main condenser, heating 20 and scrubbing the mixed vapors with steam, flashing and condensing the heated scrubbed vapor to release the ammonia content of the vapor, venting the released ammonia to waste and delivering the relatively ammonia-free condensate to the boiler feed system at a point in the system in advance of delivery of condensate to the boiler.

5. The method of removal of ammonia from boiler feed systems of power plants as claimed in claim 4 wherein the condensate from the main condenser is employed as a cooling medium to effect condensation of the vapor of the vaporized make-up water.

6. Means for removing ammonia from boiler feedwater in a boiler feed system of a power plant including in combination, a main condenser, an ejector for withdrawing non-condensed vapor and non-condensable gases from the main condenser, a secondary condenser for condensing the vapor passed through the ejector and releasing the non-condensables to waste, an evaporator for evaporating makeup water supplied thereto, means for delivering vapor from said evaporator to said secondary condenser for mixture with the vapor passed through the ejector and condensed therewith, a degasifier, a transfer pump for delivering the condensate from the secondary condenser to said degasifier, and means for delivering condensate from the degasifier to the main condenser.

7. Means for removing ammonia from boiler feedwater in a boiler feed system of a power plant including in combination, a main condenser, means for delivering condensate from the main condenser to a boiler, an ejector for withdrawing non-condensed vapor and non-condensable gases from the main condenser, a secondary condenser for condensing the vapor passed through the ejector and released the non-condensables to waste, an evaporator for evaporating makeup water, means for delivering vapor from said evaporator to said secondary condenser for mixture with the vapor passed through the ejector and condensed therewith, a degasifier, a transfer pump for delivering the condensate from the secondary condenser to said degasifier, means for delivering condensate from the degasifier into the boiler feed system at a point therein in advance of said means for delivering condensate from the main condenser to a boiler, and means for delivering condensate from said main condenser to said secondary condenser for serving as a cooling medium in the secondary condenser.

8. Means for removing ammonia from boiler

feedwater in a boiler feed system including in combination, a main condenser, means for delivering condensate from the main condenser to a boiler, an ejector for withdrawing non-condensed vapor and non-condensables from the main condenser, an inter and after condenser for condensing vapors passed through said ejector and releasing the non-condensables to waste, an evaporator for evaporating makeup water, means for delivering vapor from said evaporator to said inter condenser for mixture with the condensation from said inter condenser, a degasifier, a transfer pump for delivering condensate from the inter and after condensers to said degasifier, and means for delivering condensate from the degasifier into the main boiler feed system at a point in advance of said means for delivering condensate from said main condenser to said boiler.

10 9. Means for removing ammonia from boiler feedwater in a boiler feed system including in combination, a main condenser, means for delivering condensate from the main condenser to a boiler, an ejector for withdrawing non-condensed vapor and non-condensables from the main condenser, an inter and after condenser for condensing vapors passed through said ejector and releasing the non-condensables to waste, an evaporator for evaporating makeup water, means for delivering vapor from said evaporator to said after condenser for mixture with the condensation from said after condenser, a degasifier, a transfer pump for delivering condensate from the inter and after condensers to said degasifier, and means for delivering condensate from the degasifier into the main boiler feed system at a point in advance of said means for delivering condensate from said main condenser to said boiler.

15 20 10. The method of removal of ammonia from a boiler feed system of a power plant wherein condensate is delivered from a main condenser to a boiler which comprises withdrawing a mixture of non-condensed vapor and non-condensable gas from the main condenser of a boiler feed system, condensing the vapor and thereby releasing the non-condensable gas of the mixture to waste, supplying makeup water to the boiler feed system at a point in advance of delivery of condensate to the boiler, evaporating the makeup water, condensing the condensables of the makeup water, releasing the non-condensables from the makeup water to waste, heating and scrubbing the condensed vapor with steam and flashing 25 and condensing the heated scrubbed vapor to release the ammonia content of the vapor, venting the released ammonia to waste and delivering the relatively ammonia-free condensate to the boiler feed system at a point in the system in advance of delivery of condensate to the boiler.

30 35 40 45 50 55 60 65 70 11. The method of removal of ammonia from boiler feed systems of power plants as claimed in claim 10 wherein condensate from the main condenser of the boiler feed system is employed as a cooling medium to effect condensation of the vaporized makeup water.

12. The method of removal of ammonia from boiler feed systems of power plants as claimed in claim 10 wherein a part of the condensate from the main condenser is passed in non-contacting heat exchange relationship with the condensed makeup water.

13. Means for removing ammonia from boiler feed water in a boiler feed system of a power

plant including in combination, a main condenser, means for delivering condensate from the main condenser to a boiler, an ejector for withdrawing vapor and non-condensable gases from the main condenser, a secondary condenser, an evaporator for evaporating makeup water, means for delivering makeup water to said evaporator, means for delivering vapor from said evaporator to said secondary condenser, a degasifier, a transfer pump for delivering the condensate from the secondary condenser to said degasifier, and means for delivering condensate from the degasifier to the boiler feed system at a point in advance of said means for delivering condensate from said main condenser to a boiler.

14. Means for removing ammonia from boiler feed water in a boiler feed system of a power plant including in combination, a main condenser, means for delivering condensate from said main condenser to a boiler, an ejector for withdrawing vapor and non-condensable gases from the main condenser, a secondary condenser, an evaporator for evaporating makeup water, means for delivering makeup water to said evaporator, means for delivering evaporating steam to said evaporator, means for delivering evaporating steam from said evaporator to said main condenser, means for delivering evaporated makeup water from said evaporator to said secondary condenser, a degasifier, a transfer pump for delivering the condensate from the secondary condenser to said degasifier, and means for delivering condensate from the degasifier into the boiler feed system at a point in advance of said means for delivering condensate from said main condenser to a boiler.

15. Means for removing ammonia from boiler feed water in a boiler feed system of a power plant including in combination, a main condenser, an ejector for withdrawing vapor and non-condensable gases from the main condenser, a secondary condenser, an evaporator for evaporating makeup water, means for delivering makeup water to said evaporator, means for delivering evaporating steam to said evaporator, means for delivering evaporating steam from said evaporator to said main condenser, means for delivering evaporated makeup water from said evaporator to said secondary condenser, a degasifier, a transfer pump for delivering the condensate from the secondary condenser to said degasifier, and means for delivering degasified condensate from said degasifier to said main condenser.

16. The method of removal of ammonia from a boiler feed system of a power plant wherein condensate is delivered from a main condenser to

a boiler which comprises withdrawing a mixture of non-condensed vapor and non-condensable gas from the main condenser of a boiler feed system, condensing the vapor and thereby releasing the non-condensables of the mixture to waste, supplying make-up water to the boiler feed system at a point in advance of delivery of condensate to the boiler, passing the make-up water in non-contacting heat exchange relationship with steam to evaporate the make-up water, passing the steam used to evaporate the make-up water to the main condenser, condensing the condensables of the make-up water, releasing the non-condensables from the make-up water to waste, heating and scrubbing the condensed make-up water vapor with steam and flashing and condensing the heated scrubbed vapor to release the ammonia content of the water, venting the released ammonia to waste and delivering the relatively ammonia-free condensate to the boiler feed system at a point in advance of delivery of the condensate to the boiler.

17. Means for removing ammonia from boiler feed water in a boiler feed system of a power plant including in combination, a main condenser, means for delivering condensate from the main condenser to a boiler, an ejector for withdrawing non-condensed vapor and non-condensable gases from the main condenser, a secondary condenser for condensing the vapor passed through the ejector and releasing the non-condensables to waste, an evaporator for evaporating make-up water, means for delivering vapor from said evaporator to said secondary condenser for mixture with the vapor passed through the ejector and condensed therewith, a degasifier, a transfer pump for delivering the condensate from the secondary condenser to said degasifier, means for delivering condensate from the degasifier into the boiler feed system at a point therein in advance of said means for delivering condensate from the main condenser to a boiler, means for delivering steam to said evaporator for evaporating make-up water therein, and means for delivering condensed heating steam from said evaporator to said main condenser.
